UNITED STATES PATENT OFFICE.

JOHN HIGHAM, OF LOS ANGELES, CALIFORNIA.

BURNER.

Application filed November 15, 1924. Serial No. 750,074.

To all whom it may concern:

Be it known that I, JOHN HIGHAM, a citizen of the United States, residing at Los Angeles, in the county of Los Angeles and

5 State of California, have invented new and useful Improvements in Burners, of which the following is a specification.

This invention relates to a hydrocarbon vapor burner of the type which is particularly adapted for use in cooking operations; the present burner being especially designed to be employed in portable camp stoves as shown in my copending application for Letters Patent filed August 18, 1922, Serial 15 Number 582,631, of which this application is a continuation in part.

An object of the invention is to provide a burner of the above character in which means are provided for insuring against the flames 20 being extinguished by ordinary draughts; thus overcoming an objectionable feature common to the ordinary types of burners when used in the open and exposed to air currents.

25 Another object is to provide a vapor burner with a reservoir in which a quantity of fuel vapors intermixed with air will be held in reserve so that in event the burner is subjected to a draught tending to momentarily induce a flow of vapors from the burner faster than ordinarily would be supplied by a vapor generator, the reserve of vapors in the reservoir will be drawn upon to maintain the flame at the burner head.

30 Another object is to provide a burner embodying the above features having a plurality of burner heads including a main burner head associated with a vapor generator, and a supplemental burner head, with means whereby the supplemental burner head may be readily placed in and out of operation.

Another object is to provide a burner head which is so constructed as to insure a 45 proper mixture of air and vapors at the burner orifices.

A further object is to provide a burner head adapted to be associated with a vapor generator having burner openings of such character and arrangement as to insure proper functioning of the generator when the burner is in operation.

The invention will be best understood 50 from a consideration of the following detailed description taken in connection with the accompanying drawings forming part

of this specification with the understanding that the invention is not confined to any strict conformity with the showing of the drawings, but may be changed and modified so long as such changes and modifications mark no material departure from the salient features of the invention as expressed in the appended claims.

60 In the drawings:—

Figure 1 is a plan view of the burner with parts broken away.

Figure 2 is a view in vertical section as seen on the line 2—2 of Figure 1.

Figure 3 is a detail in vertical section as 70 seen on the line 3—3 of Figure 2.

Figure 4 is a view in vertical section of the supplemental burner head.

Figure 5 is a detail in plan as seen on the 75 line 5—5 of Figure 2 showing the manner of forming the burner openings adjacent the vapor generator.

Figure 6 is a detail in section as seen on the line 6—6 of Figure 6.

More specifically, 8 indicates the burner body, which is formed at its ends with disc-like portions 9 and 10, arranged to extend horizontally and in the direction of the length of the burner body and with the end portions disposed on substantially the same plane. The end portions 9 and 10 of the burner body afford a support and mounting for a pair of burner heads 11 and 12 respectively, and for which purpose each of the portions 9 and 10 is formed with an annular marginal flange or lip 13, and an upwardly extending annular flange 14, the outer periphery of which flange is spaced inwardly a short distance from the outer margin of the lip 13. Each burner head comprises an annular side wall 15, which seats on the lip 13 with its inner periphery spaced a short distance from the outer periphery of the flange 14. The wall 15 extends above the upper edge of the flange 14 and connects 100 with a circular top plate 16 in the case of burner head 11 and with a top plate 16' in the case of burner head 12, which top plate projects over the space bounded by the wall 15 and is spaced from the upper surface of the end portion of the burner body. The burner head thus formed, is held in place by means of screws 17, which are passed through openings in the top plates 16 and 16' 105 and which are screwed into engagement with the end portions of the burner body as particularly shown in Figure 3. The annular

110

side wall 15 of each burner head is formed with a plurality of superposed rows of perforations 18. Any suitable number of such rows of perforations may be provided as occasion may require; one or more of the rows of perforations 18 being located between the upper face of the lip 13 and the upper edge of the flange 14 and constitute air inlet openings, and one or more rows of the perforations extend between the upper edge of the flange 14 and the top plates 16 and 16' constituting burner orifices.

The burner body 8 is hollow and is formed intermediate the ends thereof with an enlarged chamber 19 constituting a vapor reservoir which chamber communicates at its opposite ends with reduced passages 20 and 21; the passage 20 being upturned and opening directly into the space within the burner head 11 and the passage 21 opening into a horizontally extending cylindrical chamber 22 formed in continuation of the passage 21, from which chamber leads a side port 23 opening into the space within the burner head 12. The outer end of the chamber 22 is closed by a cap 24 through which extends a longitudinally slidable stem 25 having a plunger valve 26 mounted thereon within the chamber 22 and which valve is adapted to be positioned to regulate the flow of fuel to the burner head 12 by sliding the valve longitudinally of the chamber 22 to vary the extent of opening of the port 23 and whereby the burner head 12 may be placed out of operation by positioning the plunger valve 26 between the port 23 and the outer end of the passage 21 so as to close the latter. The burner body is provided with a vapor and air intake indicated generally at 27 and which embodies an upwardly extending tubular projection of approximately U-shaped form including a vertically extending air intake portion 28 leading upwardly from the top face of the burner body and connecting with a horizontally and downwardly extending portion 29 opening to the chamber 19; the interior of the portion 29 constituting a mixing throat. An air inlet opening 30 is provided in the wall of the portion 28 contiguous to the top face of the burner body and formed in the upper part of the side wall of the portion 28 is an opening 31 into which projects a nozzle 32 on the end of a generating tube 33; the nozzle being arranged to project vapors horizontally into the mixing throat from whence the vapors intermixed with air drawn into the mixing throat through the air inlet opening 30 will be delivered to the reservoir chamber 19 and thence flow to the burner heads. The generating tube 33 extends over the top plate 16 of the burner head 11 and is spaced a short distance therefrom. The top plate 16 is formed with a pair of rows of elongated burner orifices 34 and

35 which are formed as particularly shown in Figures 5 and 6 and which burner orifices are adapted to direct flames against the generating tube 33.

The top plate 16 of the burner head 9 is formed with a central depression 36 constituting a generating pan to which leads a fuel supply pipe 37 opening horizontally above the pan 36. As a means for holding the generating tube 33 and the pipe 37 in proper relation to the burner head 11 a plate 38 is mounted on the top plate 16 of the burner and is held in place thereon by the screws 17; this plate being formed with a central opening 39 over the pan 36 and having side straps 40 formed thereon extending over the generating tube at each side of the opening 39 and being formed at one end of the opening with an upstanding strap 41 through which the discharge end of the pipe 37, extends and rising from the margin of the opening 39 opposite the open end of the pipe 37 is a flange 42 which serves as a flame guard.

In the operation of the invention, after initial heating of the generating tube 33, a hydrocarbon fuel is delivered to the latter from any suitable source of supply and is vaporized in the usual manner. The vapors thus formed are delivered to the interior of the burner body intermixed with air as before stated; the mixture filling the reservoir 19 and being delivered from the latter to the burner head 11 from whence the mixture is discharged through the burner orifices 18, 34 and 35 and are here ignited to set the burner head 11 in operation. If desired, a portion of the mixture is delivered to the burner head 10 on opening the port 23, and on passing through the burner orifices 18 in the burner head 10 are ignited to set the latter burner head in operation.

An important feature of the invention resides in providing a reserve supply of the mixture of hydrocarbon vapor and air in the chamber 19 so that in event a burner head is exposed to a draft tending to momentarily induce a flow of vapors from the burner head faster than ordinarily would be supplied by the generator, the reserve of vapors in the chamber 19 will be drawn upon to maintain the flame at the burner head.

While the manner of carrying the invention into effect is specifically set forth herein, I do not limit myself to the exact construction, arrangements and embodiments shown and described, as the invention is subjected to various changes, modifications and applications, and accordingly, the invention as herein defined is to be understood in a comprehensive sense.

I claim:

1. A camp stove burner comprising a pair of burner heads, a gas conduit connecting said burner heads having an enlarged cham-

ber therein, a mixing throat opening to said chamber having an air inlet, and a generator nozzle arranged to deliver vaporous fuel to said mixing throat.

5. 2. In a burner of the character described, a pair of burner heads, a gas conduit connecting said burner heads having an enlarged chamber therein intermediate said burner heads and opening thereto through 10 reduced passages, said chamber constituting a vapor reservoir, a vapor generator, and means for delivering vapors admixed with air to the enlarged chamber in said conduit.
15. 3. In a burner of the character described, a pair of burner heads, a gas conduit connecting with said burner heads having an enlarged vapor reservoir therein intermediate said burner heads and opening thereto through reduced passages, a vapor generator, 20 means for delivering vapors admixed with air to the vapor reservoir in said conduit, one of said burner heads being in open communication with said gas conduit, and a valve controlling communication between the other burner head and the conduit.

25. 4. In a burner of the character described, a gas conduit having an enlarged vapor reservoir intermediate its ends, a burner head from which lead reduced passages communicating with the vapor reservoir, a valve for

placing one of said burner heads out of communication with said vapor reservoir, a vapor generator arranged over the other burner head, and a mixing throat through 35 which vapors from said generator are delivered to said reservoir, said throat being formed with an air inlet.

5. A camp stove burner comprising a pair of burner heads, a gas conduit connecting said burner heads having an enlarged chamber therein, a mixing throat opening to said chamber having an air inlet, and a generator arranged to deliver vaporous fuel to said mixing throat, one of said burner heads 40 being in open communication with said gas conduit, and a slide valve controlling communication between the other burner head and the gas conduit.

6. In a burner of the character described, a gas conduit having a pair of disk-like head members at its opposite ends extending on a plane paralleling the length of the conduit, said conduit being formed with an enlarged chamber intermediate said head members, there being reduced passages leading from said chamber and opening to said head members, a vapor burner carried by each of said head members, and means for delivering a mixture of air and vapors to said 55 enlarged chamber in said gas conduit.

JOHN HIGHAM.
